UNITED STATES PATENT OFFICE.

JAMES H. MCEDLOWNEY, OF DETROIT, MICHIGAN.

BROOM OR WHISK.

SPECIFICATION forming part of Letters Patent No. 429,469, dated June 3, 1890.

Application filed June 27, 1888. Serial No. 278,363. (No model.)

To all whom it may concern:

Be it known that I, JAMES H. MCEDLOWNEY, of Detroit, in the county of Wayne and State of Michigan, have invented a new and useful Improvement in Brooms or Whisks; and I do hereby declare that the following is a full, clear, and exact description of the same.

My invention is an improved form of shoulder plate or piece for use in brooms. My objects are to provide a shoulder-piece which may be readily put in place and fastened upon the stock, one which, while having flexibility to enable it to be placed in position and fitted to the foundation-straws, will also be sufficiently rigid to afford a firm bearing for the outside straws and hold them in the desired form against displacement. Further, I desire to provide a shoulder which will take up little space, so that the broom can be made compact and all the outer parts will have a positive bearing from the foundation portions.

In the drawings, Figure 1 represents a portion of a broom stock or handle with the foundation-straw in place. Fig. 2 is a view of the same with my improved intermediate shoulder-plate in place, and Fig. 3 is a view of a portion of the complete broom with one side broken away to show the relative arrangement of the parts constituting said broom.

It will be understood that the invention is applicable to house-brooms particularly, but equally so to whisks and brooms of all kinds where it is necessary to provide projecting shoulders from a central supporting-stock, so as to produce a broom of broad sweep supported from a central and comparatively small handle. My invention is therefore broad enough in its scope to include all brooms of this general class.

I lay the foundation for the shoulders of my broom by securing a cluster of broom-straws to the stock *a* by means of a suitable binding-wire *b*, and these straws entirely surround the end of the handle *a*; but more are arranged upon opposite sides of the stock than upon the other two sides, so as to provide a suitable foundation for the shoulder of the broom. The improved shoulder consists of a plate *c*, which in the present case I have shown as composed of thin metal bent

to conform to the desired shape of the broom-shoulders and adapted to cover closely the projecting upper ends of the foundation structure of straws. This plate may be made in two parts and applied upon either side with a semicircular opening cut in the top of each half to fit around the stock *a*, and an upwardly-turned flange *d* may be also provided, as shown, by which it may be secured in place by a fastening-wire clamping the said flange to the stock. When the shoulder-plate is made, however, of flexible material, I simply slit it upon one side, forming a circular opening in the top, and then apply it as shown in Fig. 2, securing it in place by the same flange *d*, above referred to. It will be noticed that by reason of making the shoulder of a thin sheet of material it has sufficient flexibility to enable it to be put in place and fitted to the foundation, and when in place it affords a practically rigid bearing for the finishing straws; also, it takes up little space and the outer straws lie practically as close upon the foundation-straws at the lower edge of the shoulder as would be the case were the shoulder not used. There is consequently no looseness at this point and the broom-head is compactly and firmly made. By employing a thin sheet of material another advantage is secured, as the shoulder can be formed conveniently by pressing the material into proper form, and, as shown in Fig. 2, the shoulder covers the sides and also the edges of the foundation-straws and aids in shaping the entire broom.

Instead of being made of metal, the shoulder-plate may be made of any suitable material—such as pasteboard or papier-maché. Over this shoulder-plate the outer covering, technically known as “hurl,” is secured in position by binding around its outer ends and by stitching across the flat portion of the broom below the end of the stock, as in the ordinary manner.

A material advantage arises from the use of the shoulder-plate formed divided, as above described, for the reason that the binding-wire which is used to secure the foundation-straws in place may be brought through the slit in the plate and then used to bind together the outer layers of straws, thus avoiding cutting the wire.

I claim as my invention—

1. A broom or whisk consisting of a foundation structure of straw secured to a suitable stock, a shoulder-plate covering the same made in one piece and divided at one side with an opening in the top, and a finishing-covering, substantially as described.

2. A broom or whisk consisting of a foundation structure of straw secured to a stock, a shoulder-plate covering the same, said plate being in one piece and divided on one side

with an opening in the top conforming to the shape of the stock and having a flange *d* for the binding-wire, substantially as described.

In testimony whereof I have signed my ¹⁵ name to this specification in the presence of two subscribing witnesses.

JAMES H. McELDOWNNEY.
